UNITED STATES PATENT OFFICE.

PAUL NIEL, OF BROOKLYN, NEW YORK, ASSIGNOR OF ONE-HALF HIS RIGHT
TO GEORGE C. HOLLIS, OF SAME PLACE.

IMPROVEMENT IN PRINTING-PRESSES.

Specification forming part of Letters Patent No. 157,459, dated December 8, 1874; application filed
January 31, 1874.

To all whom it may concern:

Be it known that I, PAUL NIEL, of the city of Brooklyn, in the county of Kings and State of New York, have invented certain new and useful Improvements in Printing-Presses; and I do hereby declare that the following is a full, clear, and exact description of the same, reference being had to the accompanying drawing, which forms a part of this specification.

This invention consists in the combination, with the type-bed of a cylinder printing-press, of vertical griper-carrying arms or standards attached or secured to the bed, whereby the sheet-carrying gripers are caused to advance to the cylinder-grippers with the bed, seize the printed sheet, and recede with the bed, and deposit the said sheet on the delivery-board with the printed side up, and all this without the employment of tapes or secondary cylinders, or any extra mechanism whatever for driving the said griper-carrying arms.

In the accompanying drawing, Figure 1 is a side elevation of a type-cylinder printing-press with my improvements applied thereto, and showing the position of the parts immediately after the taking of the impression, and while the cylinder is at rest, the bed having reached its extreme limit of travel toward the rear end of the press. Fig. 2 is a plan or top view of the same. Fig. 3 is a side elevation of the press, showing the position of the parts just as the type-bed is about to proceed from the front end of the press to give the impression. Fig. 4 is an enlarged vertical sectional view of the sheet-carrying device, showing the same in the act of seizing a printed sheet from the cylinder. Fig. 5 is a perspective view of a complete stop-cylinder press containing all of my said improvements.

A A designate the side frames of the press, and B the stretchers or cross-stays. The type-bed C is of the ordinary construction, and is arranged to travel back and forth on rollers or slides or ways in the usual manner. The said type-bed is provided with the usual rack to engage cogs on one head of the cylinder D for rotating the latter, a sufficient number of the cog-teeth on the cylinder being,

however, omitted to permit the cylinder to be at rest during the return travel of the bed, and the usual stop-lever and cam may be employed for effecting the engagement of the said gearing, so as to rotate the cylinder when the bed has brought the type in proper position under the cylinder to take the impression. The cylinder-grippers a a, which hold the paper on the cylinder, may be actuated by any suitable means that will cause them, at the proper time, to seize the sheet fed to them from the feed-board E, and open at the proper time to permit the printed sheet to be taken away to be deposited on the pile. I designate a lever, which is pivoted at its upper end to the under side of the type-bed, (say as shown at e, Fig. 3,) and at its lower end to one end of a lever, J, which latter is pivoted at its other end to a central cross-stay, B, of the press-frame. I preferably construct the lever J of two separate bars, and pivot the lever I between these bars at their outer ends. L is a connecting-lever attached at one end to the crank-pin K, and at its other end it is pivoted to the lever I. This system of levers, connected and arranged as I have described them, serve to drive the type-bed at a practically uniform rate of speed during the whole time that the impression is being taken from the type, and they serve, also, to counteract or diminish the force or impetus of the crank just before the bed reaches the extreme limits of its motion in each direction, and hence the bed is caused to start and stop with a slow steady motion. M M designate the griper-carrying arms or standards. These arms or standards project up vertically from the type-bed, at opposite sides thereof, and they are securely attached to the bed near the forward end thereof. In the present instance each side frame A is provided with a longitudinal slot, p, and the lower ends of the standards are bent or made angular, and these angular or horizontal portions are passed through the said slots p and bolted to the edge or side of the bed; but of course it is obvious that the standards may be attached in various ways: for instance, the bed may have lugs cast upon it, which lugs may project through the slots p p, and standards without angular ends may be secured to

such lugs. N and O are two rods extending from the standard M on one side of the machine to the standard M on the opposite side of the machine, and to these rods are secured the sheet-carrying grippers e e'. These grippers are composed of stationary rests e and movable fingers e'. The rests e are secured to the rod N, which is stationary, and the fingers e' to the rod O, which is journaled in the said standards and arranged to oscillate, so as to permit the movable fingers to close against the rests e. It is immaterial whether the grippers be arranged to be open or closed when in their idle condition. In Figs. 1 and 3 I have shown them as being open when they approach the cylinder, where they are closed upon the edge of the printed sheet delivered to them by a bracket, Q, which trips a toe so arranged in connection with a spring that the rod O will be held with its fingers e' pressing against the rests e, as in Fig. 1, or away from them, as in Fig. 3, accordingly as the toe is tripped. Another bracket, R, at the forward end of the delivery-board serves to trip the said toe and open the grippers to drop the printed sheet at the proper place on the delivery-board or pile of sheets thereon.

It will thus be seen that in these Figs. 1 and 3 the grippers remain open or closed accordingly as the toe is tripped. In Fig. 5 the grippers are always closed when in their normal condition, and are only opened at the cylinder to permit them to seize the sheet, and at the forward end of the press, to permit them to drop the sheet. To effect this a spring is applied to the rod O, so as to continually

keep its fingers e' pressed against the rests e. The opening mechanism consists of a crank attached to the rod O, and another crank attached to the standard M, the outer ends of each being connected together by a rod, P. A roller is attached to the lower crank, and at the return stroke of the bed this roller rides upon an incline, f, and, by means of the cranks and rod P, overcomes the force of the said spring, and oscillates the rod O sufficiently to open the grippers and permit the sheet to drop, as shown in said Fig. 5. When the standards M reach the cylinder the said roller rides on an oscillating incline, g, so as to open the grippers in the manner before stated. But here the roller rides clear over the incline g at the full completion of this stroke of the bed, and therefore the grippers at once close upon the edge of the printed sheet, and on the return of the bed the roller depresses the incline g and passes over it without being affected.

What I claim as my invention, and desire to secure by Letters Patent, is—

The combination, in a printing-press, of the following elements: the stop-cylinder D, the traveling type-bed C, the rigid vertical standards M M, provided with grippers e e', the said standards being secured directly to the bed, so as to be moved bodily by the bed whenever the bed moves, and be at rest when the bed is at rest, all substantially as and for the purpose herein specified.

PAUL NIEL.
